UNITED STATES PATENT OFFICE.

DAVID M. HOLBROOK, OF PORTLAND, OREGON.

BOILER FOR INCUBATOR HEATERS.

1,417,522.

Specification of Letters Patent. Patented May 30, 1922.

Application filed January 22, 1920. Serial No. 353,258.

To all whom it may concern:

Be it known that I, DAVID M. HOLBROOK, a citizen of the United States, residing at Portland, in the county of Multnomah and 5 State of Oregon, have invented certain new and useful Improvements in Boilers for Incubator Heaters; and I do declare the following to be a full, clear, and exact description of the invention, such as will enable 10 others skilled in the art to which it appertains to make and use the same.

This invention relates to improvements in water boilers and more particularly to one intended primarily for use in connection 15 with incubators although not restricted to this particular field, the principal object of the invention being to provide an improved form of boiler which may be easily and inexpensively manufactured, yet one which 20 will be highly efficient and desirable, novel provision being made whereby an unusually great area is exposed to heat from any suitable source.

With the foregoing in view, the invention 25 resides in the novel boiler construction hereinafter fully described and claimed and shown in the accompanying drawing.

Figure 1 is a perspective view of a boiler 30 constructed in accordance with my invention.

Figure 2 is a horizontal sectional view of the boiler.

In the drawing above briefly described, the numeral 20 designates the boiler as a whole. This boiler includes a central hollow 35 cylinder 25 provided with vertically spaced horizontal flanges 26 of annular form, each of these flanges being provided with a series of tongues 27 extending radially. Two fluted sheets 28 are each formed into an arcuate series of flutes and the ends of these flutes are united with the tongues 27 by which they are closed. The flutes of the sheets 28 are spaced from the outer surface 40 of the cylinder 25 to provide a passage 26 around the cylinder which communicates with the interior of the flutes.

A water inlet pipe 30 and a water outlet 45 pipe 31 are diametrically opposed with relation to the cylinder 25 and are spaced outwardly from the latter, and these pipes are in open communication with the space 26, by means of openings 30^a and 31^a. The ends

of the pipes 30 and 31 are soldered or otherwise secured to the flanges 26 and the intermediate portions of these pipes are secured 55 by soldering or other means to the ends of the fluted sheets 28 so that the flanges 26, flutes 28 and pipes 30 and 31, are combined and united with the cylinder 25 to form a receptacle for the water to be heated. Any 60 suitable source of heat may be employed and it preferably supplies heat upwardly through the cylinder 25 and through the spaces between the outer sides of the flutes of the sheets 28, and due to the great amount of 65 area which is thus exposed to the heat, the water within the boiler will be rapidly heated. Any suitable water supply means may communicate with the pipe 30 and the pipe 31 may be connected with any desired 70 part, for instance a heating coil of an incubator. When the boiler is used in connection with incubators, brooders or the like, and the pipe 31 discharges into one end of the heating coil, the other end of this coil communicates with the pipe 30 so that the boiler 75 will produce a continual circulation of hot water.

Since excellent results have been obtained 80 from the details disclosed, they are preferably followed. I wish it understood however that within the scope of the invention as claimed, numerous minor changes may be made.

I claim:

A boiler comprising an open-ended hollow cylinder, a water inlet pipe at one side of said cylinder and a water outlet pipe at the diametrically opposite side thereof, both of said pipes being outside of said cylinder and 90 extending longitudinally thereof, a pair of fluted sheets both secured along one of their edges to one of said pipes and each secured along its opposite edge to the other pipe, said sheets extending arcuately around opposite 95 halves of said cylinder in spaced relation therewith, and end plates secured to the ends of said fluted sheets and said cylinder and forming therewith a water chamber, said pipes having openings communicating with 100 said chamber.

In testimony whereof I have hereunto set my hand.

DAVID M. HOLBROOK.
